US0D1033343S

(12) **United States Design Patent** (10) Patent No.: **US D1,033,343 S**
(45) Date of Patent: ** Jul. 2, 2024

(54) **ENERGY STORAGE POWER SUPPLY**

(71) Applicant: **Shenzhen Ampower New Energy Co., Ltd.**, Shenzhen (CN)

(72) Inventors: **Xiaofeng Liu**, Shenzhen (CN); **Heping Chen**, Shenzhen (CN); **Jiuzhi Lai**, Shenzhen (CN); **Xingqun Liao**, Shenzhen (CN); **Dangyu Pan**, Shenzhen (CN)

(**) Term: **15 Years**

(21) Appl. No.: **35/518,810**

(22) Filed: **Oct. 9, 2023**

(80) **Hague Agreement Data**

Int. Filing Date: **Oct. 9, 2023**

Int. Reg. No.: **DM/232440**

Int. Reg. Date: **Oct. 9, 2023**

Int. Reg. Pub. Date: **Oct. 27, 2023**

(30) **Foreign Application Priority Data**

Jun. 26, 2023 (CN) 202330394189.7

(51) LOC (14) Cl. **13-02**

(52) U.S. Cl.

USPC **D13/110**

Primary Examiner — Rosemary K Tarcza

(57) **CLAIM**

The ornamental design for energy storage power supply, as shown and described.

DESCRIPTION

1. Energy storage power supply

1.1 : Front

1.2 : Back

1.3 : Left

1.4 : Right

1.5 : Top

1.6 : Bottom

1.7 : Perspective

1.8 : Perspective

1.9 : Perspective

Use of this product design: This design product is used as an energy storage power, to store and provide electrical energy. Design essentials of this product design: The shape. Picture or image that best illustrates the design essentials: Perspective view 1.7.
